CLAIM

The ornamental design for a push rake, as shown and described.

DESCRIPTION

FIG. 1 is a perspective view of a push rake showing my new design;

FIG. 2 is a front elevational view thereof;

FIG. 3 is a left side elevational view thereof, the right side being a mirror image of that shown;

FIG. 4 is a top plan view thereof; and

FIG. 5 is a rear elevational view thereof.

The handle portion is shown broken-away in FIGS. 1, 3 and 4 to indicate indeterminate length.
